ADOLFO CAMPOS AND ANGEL RAMIREZ, OF NEWARK, NEW JERSEY

SMOKER'S NOVELTY

Application filed February 11, 1930. Serial No. 427,507.

This invention relates, generally, to novelties, and the invention has reference, more particularly to a smoker's novelty.

The principal object of the present invention is to provide a novel smoker's novelty which provides a storage means for cigarettes adapted to retain cigarettes straight and fresh and having easily operable means for ejecting cigarettes for use.

Another object of the present invention is to provide a smoker's novelty having a cigarette lighter provided with cartridge means adapted to store flint refills and easily operable when desired to readily discharge a refill into the lighter for use therein.

Still another object of the present invention lies in the provision of a smoker's novelty having a supporting base provided with a flash light and battery therefore, said flash light enabling the use of said novelty in the dark and being useful for other purposes, said base also providing space for the storage of suitable articles.

A further object of the present invention is to provide a smoker's novelty of the above character which is light in weight, is readily portable, being suitable for carrying in whole or in part in one's pocket, and which is of simple, strong construction and reliable in operation.

Other objects of the present invention, not at this time more particularly enumerated, will be clearly understood from the following detailed description of the same.

The invention is clearly illustrated in the accompanying drawing, in which:—

Fig. 1 is a view in side elevation of the smoker's novelty of this invention, the same being illustrated in open cigarette ejecting position;

Fig. 2 is an enlarged view with parts broken away of the structure of Fig. 1, the same being illustrated in closed condition;

Fig. 3 is a part sectional view taken along line 3—3 of Fig. 2; and

Fig. 4 is a view in rear end elevation with parts broken away of the structure shown in Fig. 2.

Similar characters of reference are em-

ployed in all of the hereinabove described views to indicate corresponding parts.

Referring now to the said drawings embodying the preferred form of the invention, the reference numeral 1 designates the smoker's novelty as a whole. The smoker's novelty 1 comprises a base 2 supporting a detachable casing 3 which has a removable cover 4 provided with a cigarette lighter 5.

The base 2 comprises a hollow body 6 with a closed bottom 7 and having an open top covered by a removable cap 8. Cap 8 is formed with a depending peripheral flange 9 which fits over and frictionally engages the exterior upper portion of the body 6, thereby retaining the cap upon this body. An apron 11 is formed exteriorly of the body 6 and extends downwardly to provide a supporting means for this body.

The body 6 is adapted to receive and retain a flash light battery 12, one spring contact 13 of which engages the base of an electric light bulb 14 which is suitably threaded through an aperture provided in the forward end of body 6. The other spring contact of battery 12 is adapted to be engaged when desired by a suitable contact member carried by a knurled slide button 15 mounted on the base 2 to thereby effect the illumination of bulb 14. Bulb 14 may be employed to provide a light when the smoker's novelty is used in darkness, thereby enabling the user to see to remove and light cigarettes carried by the novelty.

The hollow body 6 is of sufficient dimensions to provide a space above the battery 12 suitable for the reception of such articles as a note pad 19 and pencil 10. By merely removing cap 8, access is obtained to such articles as are contained in the space above the battery 12. End spring fingers 16 and side spring fingers 17 are pressed outwardly of the cap 8 and extend upward substantially at right angles to the upper surface of this cap. Spring fingers 16 and 17 are adapted to releasably retain the casing 3 upon the base 2. Casing 3 may be readily detached from base 2 by pulling upwardly upon the same so as to overcome the frictional grip 100

of fingers 16 and 17 upon the outer surface of the casing.

Casing 3 is hollow and is adapted to hold cigarettes 18. This casing is shaped so as to receive the contents of an entire pack of cigarettes at one time, if desired. Casing 3 is closed at its bottom and has an open top which is normally closed by the removable slide cover 4. The upper edge of casing 3 is formed with a peripheral bead 23 extending around and projecting outwardly from the outer surface of this casing. The slide cover 4 is formed with depending guide flanges 24 at its sides which are adapted to engage over the bead 23, thereby retaining the slide cover 4 upon the casing 3. The forward end of the slide cover 4 is similarly provided with a depending stop flange 25 which limits the motion of the slide cover when the latter is slid endwise onto the top of casing 3. To remove the slide cover 4 from the casing 3, it is merely necessary to slide the cover forwardly and endwise with respect to the casing or to the right as viewed in Fig. 2, the guide flanges 24 sliding over the bead 23. This movement of the slide cover 4 is permitted since the rear end of this cover is not provided with a depending flange.

30 A double bowed spring 20 is contained within casing 3 and bears at one end against the rear end wall 21 of this casing and at its other end against a presser piece 22. Presser piece 22 is channel shaped and extends vertically within the casing 3. Presser piece 22 is urged towards the forward end of the casing 3 by the action of spring 20 and as this presser piece bears against the cigarettes 18, it tends to move these cigarettes toward the right as viewed in Fig. 2. A chain 26 is secured to the presser-piece 22 midway of the height thereof and extends rearwardly through a guide aperture 27 provided centrally of the double bowed spring 20 and through an aperture 28 provided in the rear end wall 21. By pulling outwardly upon chain 26 the presser-piece 22 may be pulled toward the rear wall 21 to thereby enable the ready insertion of cigarettes into the casing 3, the slide cover 4 having been previously removed.

In order to retain the presser piece adjacent the wall 21 and out of the way while the casing 3 is being loaded with cigarettes, a stop slide 30 having a V-slot 31 therein, is adapted to engage the chain 26, thereby holding the presser piece in its retracted position adjacent the wall 21. Stop slide 30 is slidably mounted within a guide member 33 which is attached, as by screws, to the exterior of rear wall 21. Stop slide 30 is provided with an operating knob 32. By pushing stop slide 30 upwardly by means of knob 32, the V-slot 31 engages chain 26, thereby retaining the presser piece 22 in its retracted

position adjacent the wall 21, thereby enabling the ready insertion of a pack of cigarettes into the open upper end of the casing 3. When the cigarettes have been inserted into the casing, knob 32 is pushed downwardly so that chain 26 is released with the result that spring 20 causes presser piece 22 to urge the cigarettes toward the forward end of the casing while maintaining the cigarettes in a straight upright condition.

A cigarette ejector 34 is positioned in the forward portion of the casing 3 and has a handle bracket 29 secured to the forward face thereof, as by rivets. Bracket 29 has end lugs 29' which project through vertical slots 80 provided in the front end wall of casing 3 and carry an operating handle 35. Cigarette ejector 34 is of substantially channel shape and comprises a web portion 36 positioned adjacent the forward end of the casing 3 and flanges formed at the sides of this web which flanges extend rearwardly for a short distance adjacent the side walls of the casing 3. Web 36 is provided with a cut-out portion 37 to accommodate the user's thumb when using the ejector. A transversely extending pin 38 is positioned at the lower end of ejector 34 and has its ends secured within apertures provided in the side flanges of the ejector. Transverse pin 38 is adapted to engage the lower ends of the cigarettes 18 and to be moved upwardly with the ejector, thereby operating to push these cigarettes outwardly through an opening 39 provided in the slide cover 4. Opening 39 is normally closed by a hinge cover 41 which is hingedly connected at 42 to the slide cover 4. A coil spring 43 surrounds the pintle of the hinge connection 42 and acts to normally retain the hinge cover 41 in closed condition, thereby sealing casing 3 and serving to retain the cigarettes therein in a fresh condition. An inclined guide plate 44 is positioned within casing 3 and rests upon the bottom thereof and is adapted to guide the cigarettes 18 onto the top of the transverse pin 38. Guide plate 44 has a downwardly offset extension 45 at its forward end which projects under pin 38 and serves to support the forward end of guide plate 44.

The cigarette lighter 5, provided on slide cover 4, comprises a snuffer 46 which has an operating knob 57 and is pivoted on a pin 47 carrying a tooth friction wheel 48. A flint stick 49 contained within a sleeve 50 is urged into engagement with the tooth friction wheel 48 by a compression spring 51. Compression spring 51 is retained in assembled relation within the sleeve 50 by a cap 55 which is threaded upon a reduced extension 56 of the sleeve 50. Sleeve 50 is partly cut away at 52 providing an inlet opening for receiving flint stick refills. A flint stick cartridge 53 serves to replenish the flint sticks as they are used up in the lighter.

Cartridge 53 has a hook portion 60 which is pivotally mounted within a circumferentially extending groove provided in the exterior wall of sleeve 50. Flint stick cartridge 52 is adapted to receive a plurality of flint sticks 49 through an aperture 54 provided in the outer end thereof.

To replenish a flint stick in the lighter, it is merely necessary to remove the cap 55, thereby releasing spring 51 and then turning the cartridge 53 upwardly so that a new flint stick 49 drops through the cut-away portion 52 into the interior of sleeve 50, whereupon compression spring 51 and cap 55 are again assembled with sleeve 50.

By exerting thumb pressure upon the operating knob 57 the snuffer 46 is turned upwardly about its pivotal pin 47 causing the friction wheel 48 to be revolved with respect to the flint stick 49, thereby causing a spark to be produced and serving to ignite the wick 58 of the lighter.

In use, the novel smoker's novelty of this invention may be carried about either in whole or in part or the same may be conveniently employed upon a smoking stand. To eject cigarettes from casing 3 it is merely necessary to push upwardly upon the operating handle 35, whereupon the transverse pin 38 acts to push two cigarettes at a time upwardly through opening 39 and by swinging hinge cover 41 upwardly disposes the upper end portions of the cigarettes convenient for withdrawal from the casing 3, whereupon the lighter 5 may be used for lighting the cigarette, as desired.

It will be noted that the smoker's novelty of this invention provides for the ready storage of cigarettes while retaining them in a fresh wholesome condition, since the casing 3 is completely closed. Also the presser piece 22 acts to maintain the cigarettes straight and upright within this casing, ready for use at all times. A window 61 may be provided in casing 3, if desired, so that the quantity of cigarettes within this casing may be observed at any time.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:—

1. In a smoker's novelty, a cigarette lighter comprising, a wick element, a friction wheel, a guide cylinder having an open end adjacent said friction wheel, a flint stick slidably mounted within said guide cylinder and adapted to engage said friction wheel, spring means contained within said guide cylinder for urging said flint stick into engagement

with said friction wheel, means for revolving said friction wheel so as to cause the latter to rub said flint stick and effect the lighting of said wick element, said guide cylinder having an aperture in the side wall thereof and a flint stick cartridge pivotally connected to said guide cylinder and adapted to contain additional flint sticks, said flint cartridge being turnable upwardly about its pivotal connection with said guide cylinder to cause a flint stick to drop downwardly through the aperture in said guide cylinder to thereby replenish used up flint sticks.

2. In a smoker's novelty, a cigarette lighter comprising, a wick element, a friction wheel, a horizontal guide cylinder having an open end adjacent said friction wheel, a flint stick slidably mounted within said guide cylinder and arranged to engage said friction wheel, spring means contained within said guide cylinder, a cap threaded on the outer end of said guide cylinder for compressing said spring, whereby the latter urges said flint stick into engagement with said friction wheel, means for revolving said friction wheel so as to cause the latter to rub said flint stick and effect the lighting of said wick element, the upper portion of said guide cylinder being cut away adjacent said friction wheel, and a flint stick cartridge pivotally mounted on said guide cylinder at the cut away portion thereof, said flint stick cartridge being arranged to contain a plurality of reserve flint sticks and being turnable upwardly about its pivotal connection with said guide cylinder to cause a flint stick to feed downwardly through the cut away portion of said cylinder to thereby replenish used up flint sticks.

In testimony, that we claim the invention set forth above we have hereunto set our hands this 10th day of February, 1930.
